UNITED STATES PATENT OFFICE

NELL Q. DONNELLY, OF KANSAS CITY, MISSOURI

GARMENT

Application filed March 3, 1930. Serial No. 432,601.

This invention relates to improvements in garments and more particularly to garments for ladies' wear, and the principal purpose is the provision of a one piece, loose-fitting, 5 trousered or pajama-type garment which is adapted for many and various uses such as lounging, negligee, house and service wear.

A further object of this invention is the provision of such a garment which is neat 10 and attractive in appearance, becoming to the wearer and still lends itself to commercial production on a large scale. The garment is easy to put on and take off, and simple and effective in its fastening means. The invention 15 may be embodied in a number of various forms and designs without departing from the basic idea.

Another object is the provision of a pajama garment requiring only one fastening 20 in the back and one on each side, rendering it easy to get into and out of, and when on the wearer and fastened it allows great freedom of movement without disarranging the garment, thereby insuring a constant neat 25 appearance even after wearing several hours when actively engaged in housework, strenuous exercise or wearing on the beach.

A further object of this invention is the provision of such a garment which includes 30 a waist portion and a trousers portion, the waist portion being of wrap-around and tie-around construction and the front of the trousers portion being preferably secured permanently to the waist portion at the 35 front, the back or seat flap of the trousers being provided with an elastic for fitting purposes and having a detachable connection with the waist portion of the garment.

To the accomplishment of the foregoing 40 and such other objects as may hereinafter appear, this invention consists in the construction, combination and arrangement of parts hereinafter described and then sought to be defined in the appended claims, reference being had to the accompanying drawings forming a part hereof and which shows, 45 merely for the purpose of illustrative disclosure, a preferred embodiment of my invention, it being expressly understood, however, 50 that various changes may be made in prac-

tice within the scope of the claims without digressing from my inventive idea.

In the drawings—

Figure 1 represents a perspective view of one form of garment constructed to embody 55 my invention.

Figure 2 is a front elevation thereof.

Figure 3 is a rear elevation thereof.

Figure 4 is a vertical longitudinal cross section of the garment taken on line 4—4 of 60 Figure 2.

Figure 5 represents a rear view of the garment with the waist portion thrown open to disclose the trousers support.

Figure 6 represents a transverse horizontal 65 cross section taken on line 6—6 of Figure 4.

Referring now to the drawings, the numeral 1 designates the blouse or waist portion of the garment as a whole and 2 the trousers portion of the garment as a whole. These 70 parts are preferably secured or connected together at the waist and at the front only, as at 3. Of course, it is to be expressly understood that instead of being made of separate pieces of material or elements, the parts may 75 be made of one piece and permanent connection at the waist provided in that fashion, if desired.

The waist itself is composed of the front 80 piece or panel 4 and the side or back pieces 80 or panels 5 secured thereto. The front panel is extended upward as at 6 to connect with the top edge of the side or back panels 5 and also to provide room for the armholes 7. The back or side panels are of such shape as to 85 fit across and cover the back of the wearer, and in the form shown, extend diagonally in a sort of a crossed arrangement. A single fastening means 8 is all that is necessary to connect the side and back panels at the back 90 of the neck. Each of the side or back panels is provided with an elongated and extended belt element 9. These belt elements are designed to extend from the rear of the waist around to the front and to be tied or otherwise 95 suitably connected together as at 9' to define the waistline of the garment and also to add an attractive feature to this construction. In order to facilitate this, one of the side or back panels is provided with the slot or open- 100

ing 10 to permit the passage therethrough of one of the belt elements 9. This construction gives complete and ready adjustment of the waist portion of the garment to various sizes and types of figures.

5 As stated before, the trousers element is either secured to the waist element at the front or else made integral therewith to form a one-piece garment. This trousers element 10 has the rear or seat flap 11, which is preferably provided with the elastic material 12 within a hem 13 along the top edge thereof and the upper corners of this flap are adapted to be supported by and secured to suitable 15 fastening means 14. In the form shown these members 14 each include a tape 15 connected to the inside of the front of the waist or blouse portion and having a button or other suitable fastening means 16 on the end thereof, the 20 flap being provided with a buttonhole 17 for each fastening means. Of course, any other form of complementary fastening means may be provided.

25 The waist portion at the rear is of sufficient length to overlap the rear portion of the trousers construction and the waist part of the trousers construction, being provided with the elastic, will insure that part of the garment being held up in proper position 30 at all times.

35 This garment is designed for various uses such as home use for work and lounging purposes to take the place of lounging pajamas and beach pajamas or in fact almost any informal or domestic use. This garment will fit 40 various sizes and figures without modification as the adjustable belt of the waist portion and the resilient waist band of the trousers portion will permit considerable variation in any one size of garment. It is neat and attractive in appearance and may be made in various designs and combinations of material, and is practical in that it is a cover-all garment completely covering the person 45 and the under garments of the wearer. However, it is cool and comfortable due to its simple construction and the minimum number of parts necessary. The manner in which the trousers are supported by tabs attached 50 to the front of the blouse contribute to the comfort and adjustability of the garment. This same adjustability is carried out in the type of back closing, that is, one side passing over the other and through the slot in the 55 bodice part. The elastic at the waist line of the back part of the trousers makes the waist line adjustable to many types of figures.

60 Therefore, through the manner of joining the blouse and trousers in the front by tabs; the particular type of back closing; and elastic at the waist line of the back of the trousers, this garment is not only comfortable but adjustable in the bust, waist line and hips and, consequently, will fit a great many types 65 of figures without any alteration.

What I claim is:—

1. A one piece pajama-type garment comprising a blouse portion and a trousers portion permanently connected together, the blouse portion being disconnected from the trousers portion at the rear and being of wrap-around type, said blouse portion being provided with belt members adapted to tie therearound and said trousers portion being provided with a rear flap portion having resilient means at the waistline thereof, and cooperating fastening means between the flap portion and the blouse portion. 70

2. A garment of the character described including, in combination, a blouse portion and a trousers portion having its front part permanently connected to the blouse portion, said blouse portion including a pair of back panels connected to the sides thereof but free and disconnected at or adjacent the waist, a cooperating belt member connected to each back panel and adapted to be wrapped and tied around the waist to cause said back panels to overlap each other and the top of the trousers portion, and fastening means for connecting said back panels together at the back near the top thereof, said trousers portion being provided with a free rear flap and supporting and fastening means connected to the inside of the blouse portion to hold said flap in position under said back panels, and a resilient element provided in the upper edge of the rear flap to hold the flap up under the overlapped back panels of the blouse portion. 80

3. A one piece pajama-type garment comprising a blouse portion and a trousers portion permanently connected together, the blouse portion being disconnected from the trousers portion at the rear and being of wrap-around type, said blouse portion being provided with belt members adapted to tie therearound so as to adapt the blouse comfortably to various figures, and said trousers portion being provided with a rear flap portion having resilient means at the waistline thereof, and cooperating fastening means between the flap portion and the blouse portion. 90

4. A one piece pajama-type garment comprising a blouse portion and a trousers portion permanently connected together, the blouse portion being disconnected from the trousers portion at the rear and being of wrap-around type, said blouse portion being provided with belt members adapted to tie therearound and said trousers portion being provided with a rear flap portion having resilient means at the waistline thereof, and cooperating fastening means between the flap portion and the blouse portion including a pair of tape supporting elements secured to the inside of the front of the blouse and provided with fastening means near the end thereof and a complementary fastening element on the flap portion for each tape supporting element. 100

5. A one piece pajama-type garment comprising a blouse portion and a trousers portion permanently connected together, the blouse portion being disconnected from the
5 trousers portion at the rear and being of wrap-around type, said blouse portion being provided with belt members adapted to tie therearound so as to adapt the blouse comfortably to various figures, and said trousers
10 portion being provided with a rear flap portion having resilient means at the waistline thereof, and cooperating fastening means between the flap portion and the blouse portion including a pair of tape supporting elements
15 secured to the inside of the front of the blouse and provided with fastening means near the end thereof and complementary fastening elements on the flap portion.

In testimony that I claim the foregoing, I
20 have hereunto set my hand this 3rd day of February, 1929.
